UNITED STATES PATENT OFFICE.

ALFRED NORTON GOLDSMITH, OF NEW YORK, N. Y., ASSIGNOR, BY MESNE ASSIGNMENTS, TO RADIO CORPORATION OF AMERICA, A CORPORATION OF DELAWARE.

VARIABLE ELECTRICAL CONTROLLING ELEMENT.

Application filed July 31, 1919. Serial No. 314,480.

To all whom it may concern:

Be it known that I, ALFRED N. GOLDSMITH, a citizen of the United States, and a resident of the borough of Manhattan, city, county, and State of New York, have invented certain new and useful Improvements in Variable Electrical Controlling Elements, of which the following is a specification accompanied by drawings.

10 This invention relates to variable electrical controlling elements, but more particularly to apparatus and devices for varying inductance which may find application for instance, among other arts, in radio signaling systems, it being understood that the devices may be used wherever found applicable in electrical systems of any character.

20 The primary object of the invention is to provide a ready means of changing the inductance of the desired circuits conveniently and continuously, and I have found that an inductance in the field of which a conducting shield forming a short circuited secondary, is adapted to be moved in one direction or another, or periodically introduced or withdrawn, forms an efficient and satisfactory variable inductance. Obviously my invention contemplates relative movement between a coil or coils and a shield or 25 shields, however this may be accomplished.

30 In order to more readily understand my invention, I have shown it applied to a wave changer for radio signaling apparatus, both for receiving and transmitting, but this 35 is merely for purposes of illustration, in order to indicate some of the uses and advantages of the invention.

Referring to the drawings,

40 Fig. 1 is a view showing means for varying the coupling of a receiving station provided with a variable shield inductance;

Fig. 2 is a diagrammatic view partly in perspective showing a variable loading inductance and a variable coupling;

45 Figs. 3 and 4 are diagrammatic representations of oscillating vacuum tube transmitters to which the invention is applied; and

50 Fig. 5 is a diagrammatic representation of a quenched gap transmitter to which the invention is applied.

Referring to the drawings and at first more particularly to Fig. 1, A represents an antenna grounded at B coupled to suitable receiver circuits having the variable con-

denser F, detector G, and the telephones H. 55 The usual variable condenser J is shown in the antenna A. PQ represent respectively primary and secondary coupling coils of a transformer between which is a shield O which may be in the form of a disk of conducting material as copper and may be of any suitable configuration.

In Fig. 1 is shown a mode of varying the mutual inductance between the coupling coils P and Q by the motion in their mutual field of the shield O. The mutual field of magnetic lines of force from coil P which passes through coil Q, as distinguished from the self-field of each coil, also passes at least in part through the conducting shield O. 65 As the shield O is moved or rotated relatively to or about any axis O' in substantially any fashion, the interlinkage of mutual flux through it will alter and in consequence its shielding effect upon coil P will 70 be altered. I thus have a means of continuously varying the mutual inductance between two coils by the motion in their mutual field of a shield of conducting material. This principle has been previously utilized 75 by me for another purpose in my copending applications Serial #313,691 for my modulation receiver and Serial #314,031 for tone transmission from continuous waves.

This principle as applied to varying the 85 self inductance of a coil is made the subject matter of my copending application Serial No. 314,479.

In the present application the coils P and Q and shield O together form a variable 90 mutual inductance of the shield type. The mutual inductance is that between the coils P and Q and the shield may consist as shown of the disk O, but may take any other desired or suitable form, some of which are 95 illustrated herein, and to be described. The shield may be progressively inserted between the coils P and Q, which may, if desired, be flat spirals as shown in Fig. 2 and when the shield is entirely inserted as shown in Fig. 1, 100 the mutual inductance will be a minimum as explained in connection with my modulation receiver in my application Serial #313,691.

It is to be understood that the shield O 105 may be moved or manipulated by any suitable form of operative mechanical means (not shown), and the outline or contour of

the shield, and its conductivity are determinable at will, so that practically any desired law of inductance variation with a given series of settings of the shield may be obtained. Furthermore, practically any law of mutual inductance variation can be similarly obtained by the proper choice of the same conditions.

10 The entrant edge or advancing contour of the shield of conducting material which passes over or into the inductance is of importance in that it determines, in part, the law connecting motion of the shield and the inductance of the coil which is being shielded. The drop of inductance with a curved edge is more gradual and extends more nearly evenly over the entire range of motion of the shield. Another even more important advantage is that the increase in 20 resistance during shield insertion, as well as the terminal resistance is considerably less. This is to be ascribed to the nature of the eddy current paths in the shield, which becomes clear upon a detailed examination of them.

In Fig. 2, in addition to the shield inductance formed by the coil T and shield v, I have illustrated a combined arrangement of shield inductances for the coupling coils 30 8 and 9 which is also a variable shield mutual inductance, because the primary coil 8 which is variable by means of the shields, is coupled to the similarly variable secondary 9 through a variable shield mutual inductance.

35 In this instance the shields 10, 11, and 12 are arranged adjacent and between the coils 8 and 9 as indicated and adjustably mounted by means of set screws 13 on a common operating shaft adapted to be manipulated 40 by the handle 15 to swing the shields into and out of shielding position. The shields 10, 11, and 12 need not necessarily be on one operating shaft, but may be independent of one another or else mutually interconnected in any desired manner. The construction shown forms a uni-control variable coupler and variable inductance combined. In Fig. 2, I have illustrated an aperiodic secondary 9 across which in this 50 instance, is connected the detector G and fixed condenser 16, the telephones H being connected as shown across the condenser 16. If desired the shaft w of the shield v for the loading coil T may be operatively connected 55 to the shaft 14 of the shields 10, 11, and 12 by any suitable means as the belt or chain 16', so that a completely uni-control device is produced. As the wave length is increased by increasing the inductance of all 60 the coils T, 8, and 9, the coupling between coils 8 and 9 will also be automatically increased by the proper amount. It is to be understood that the design of Fig. 2 is merely illustrative and the arrangement and 65 shape of the various shields, shield induc-

tances, and variable shield mutual inductances may be varied in accordance with any of the modifications herein disclosed, or changed in various particulars in accordance with the principles of my invention, without departing from the spirit of the invention as claimed by me in the claims forming part of this specification.

Fig. 3 shows the invention applied to a form of unicontrol bulb or vacuum tube 75 radio telegraph transmitter, which may be made a radiophone transmitter by suitable alterations in the circuits, well understood by those skilled in the art, which however, do not affect the principles of my invention.

In Fig. 3, the oscillating vacuum tube represented at 17 may be of the three element or any other suitable type, having the heated filament 18, the plate 20 and the grid 19. The circuit shown in the example may be termed a series plate feed circuit, and is known as such, since the plate circuit generator 21 is in series with the oscillating antenna circuit. The regenerative coupling 85 between the coupling coils 22 and 23, by means of which the plate and grid circuits are also coupled, and sustained oscillations maintained, may be of the combined shield inductance and variable shield mutual inductance type as illustrated in Fig. 2 for 95 instance, but is here shown in Fig. 3 diagrammatically for convenience and to avoid repetition of drawings. It is to be understood however, that any of the other forms of inductance controlling devices illustrated 100 and described may be used as desired, so that, as the antenna wave length is altered by changes in the shield inductance formed by coil 22 and its shields, corresponding and suitable changes are made in the grid circuit shield inductance formed by coil 23 and 105 its shields, and also in the shield coupler between coils 22 and 23. The shield inductance formed by the loading coil 24 and shield 25 may be used in the antenna as shown if 110 desired. Though the end connections to coil 22 are shown as movable, they are, in general, fixed once for all when the set is connected to a given antenna for use 115 throughout a given wave length range. All variation of wave length within this range thereafter may, in general, be obtained by motion of the shields 10, 11, and 12.

In Fig. 4 is shown another bulb or vacuum tube oscillator of the uni-control type, but in this instance the circuit is of the parallel plate feed form, in which the plate circuit generator 21, in series with the radio frequency choke coil 26 is connected to the filament 18 and plate 20 of the tube in parallel with the oscillating circuit inductance 27, and the remainder of the oscillating circuit including the antenna A and inductance 28. Variable shields 29 and 30 are diagrammatically shown for the inductances 125 130

or coupling coils 27 and 28. The tuning of the circuits by means of the inductances 27 and 28 and the maintenance of a suitable regenerative coupling between the inductances, which are respectively in the plate and grid circuits, is obtained by manipulation of the shields 29 and 30, which also control the mutual inductance of the coupler. As mentioned in connection with Fig. 3, the 10 terminal connections to coils 27 and 28 are, in general, stationary when once the set is installed, and shield movement only is depended upon for wave changing.

In Fig. 5 the invention is shown applied to 15 a uni-control quenched spark transmitter, in which the alternator 31 is connected through the key 32 to the primary 33 of the high tension transformer, the secondary 34 of which includes in its circuit the secondary 20 capacity 35, the quenched spark gap 36, and the primary coupling coil 38, coupled to the antenna inductance 39. The inductances 38 and 39 are shown diagrammatically as shield inductances, as indicated by the 25 shields 40, 41, and 42, and this construction also forms a combined shield inductance and variable shield mutual inductance in accordance with Fig. 2 for instance, although other forms of devices may be used 30 as hereinbefore described and explained.

The various forms of my invention contemplate a variable coupler, which I have termed a shield coupler; or they involve both a variable inductance and a variable 35 coupler which I have termed a combined shield inductance and variable shield mutual inductance. The principles of my invention involve a coil or coils in the magnetic field of which a body or bodies of conducting material are moved or inserted in 40 such manner that the magnetic fields of the eddy currents induced in such bodies change the effective inductance, mutual inductance, or both, of the coil or coils, as said eddy currents are progressively altered by the motion, insertion, or withdrawal of said conducting body or bodies.

While I have shown various special forms 50 of application of a shield coupler to uni-control or multi-control receivers and transmitters of various types, I am not to be restricted to the particular forms shown, but desire to be understood as including within my invention, shield couplers, or combinations 55 of these in different forms in any receiver or transmitter or any other electrical device to which they are applicable.

I claim and desire to obtain by Letters Patent the following:

60 1. A variable radio coupler comprising coaxial current carrying coupling coils and a parallel shield of conducting material in the mutual field of the coils, said coils and shield being relatively movable in a direction transverse to the axis of the coils where-

by the coupling between the coils may be varied.

2. A variable radio coupler comprising high frequency coaxial current carrying coupling coils and a parallel shield of conducting material intermediate to and in the mutual field of the coils, said coils and shield being located in close proximity to each other and relatively movable in a direction transverse to the axis of the coils whereby the shield may be withdrawn to obtain maximum variation of the coupling between the coils.

3. A variable radio coupler comprising a pair of radio frequency coaxial current carrying coupling coils and a parallel short circuited secondary of conducting material intermediate to the coils, said coils and secondary being relatively movable in a direction transverse to the axis of the coils and located in close proximity to each other.

4. A variable coupler comprising coaxial radio frequency current carrying coupling coils fixed relative to each other, and a short circuited secondary of conducting material in the mutual field of the coils, said coils and secondary being located in close proximity to each other and relatively slidable in a direction transverse to the axis of the coils, whereby the secondary may be withdrawn to obtain maximum variation of the coupling between the coils.

5. A variable coupler, comprising coaxial coupling coils, and a flat shield of conducting material in the mutual field of said coils, said coils and shield being slidable relative to each other in a direction transverse to the axis of said coils.

6. A variable coupler, comprising flat coaxial coupling coils, and an intermediate 105 flat shield of conducting material substantially parallel thereto in the mutual field of the coils, said shield being adjustable in a direction transverse to the axis of the coils to cover various sections of the surface of the coils.

7. A variable coupler, comprising flat coaxial coupling coils and a flat shield of conducting material substantially parallel thereto in the mutual field of the coils, said 115 conducting body being rotatable in a plane transverse to the axis of said coils.

8. A variable coupler, comprising coaxial flat coupling coils and an intermediate flat shield of conducting material substantially parallel and in close proximity thereto, said coils and shield being slidable relative to each other in a direction transverse to the axis of said coils, to cover various sections of the surface of the coils.

9. A variable coupler comprising current carrying coupling coils fixed relative to each other and a parallel short circuited secondary of conducting material in the mutual field of the coils, said coils and secondary 130

- 4
- being relatively movable in a direction transverse to the axis of the coils and located in close proximity to each other.
10. A variable coupler comprising a plurality of coaxial current carrying coupling coils and a plurality of parallel shields of conducting material adjacent said coils, said coils and shields being relatively adjustable in a direction transverse to the axis of said 10 coils for varying the coupling.
11. A variable coupler comprising a plurality of coaxial current carrying coils, a shield of conducting material in the mutual field of two of the coils, a second shield of 15 conducting material in the self field of one of the coils, and means for relatively adjusting said shields and coils in a direction transverse to the axis of said coils.
12. A variable coupler comprising a plurality of coaxial current carrying coils, a 20 shield of conducting material parallel to and in the mutual field of two of said coils and a second shield of conducting material parallel to and in the self field of another of said coils and means for relatively adjusting said shields and coils in a direction transverse to the axis of the coils.
13. A variable coupler comprising a plurality of flat coaxial current carrying coils, a flat shield of conducting material parallel to and in the mutual field of two of said coils and a second flat shield of conducting material parallel to one of said coils and means for relatively adjusting said shields and coils in a direction transverse to the 25 axis of the coils.

In testimony whereof I have signed this specification.

ALFRED N. GOLDSMITH.
